(57) CLAIM

The ornamental design for a personal carrying bag, as shown and described.

DESCRIPTION

FIG. 1 is a front view of a personal carrying bag, showing my ornamental design thereof;

FIG. 2 is a rear view thereof, with a back strap unattached; FIG. 3 is a rear view thereof, with a back strap attached; and, FIG. 4 is a front side perspective view thereof in an alternate configuration.

The broken lines in the drawings are for the purpose of illustrating stitching and form no part of the claim.
